his Attorney.

UNITED STATES PATENT OFFICE.

STANLEY SOLARZ, OF ST. PAUL, MINNESOTA.

DETACHABLE SHOE-HEEL.

1,383,436.

Specification of Letters Patent.

Patented July 5, 1921.

Application filed March 3, 1921. Serial No. 449,281.

To all whom it may concern:

Be it known that I, STANLEY SOLARZ, a citizen of Poland, residing at St. Paul, in the county of Ramsey and State of Minnesota, have invented certain new and useful Improvements in Detachable Shoe-Heels, of which the following is a specification.

This invention relates to new and useful improvements in means for detachably securing heels to shoes, its main object being to provision of heel fastening devices, requiring in their application absolutely no cutting away of parts of the shoe proper, such as sinking large cavities, or embedding parts to render them flush with the surface of the shoe.

When devices of this kind require careful fitting, skilled labor is required thereby precluding its popular use.

An object of my invention, is to provide a rubber heel, which may be purchased and be applied by any unskilled person, the device being so simple in construction that it may be laid flatly on the heel portion of the shoe to bring its edges even with those of the latter, and then be tapped gently with a hammer, whereby the shoe is caused to be plainly marked or indented, so that the part of the device to be secured to the shoe, may be positively located and simply pegged directly upon the top surface of the shoe, which concludes the operation.

A further object of the invention is to provide an element to be cast into the rubber heel, which will have no large flat surface areas such as flat plates, whereby the rubber, as is well known, becomes easily separated from the metal and tends to tear the heel asunder, the heel anchor shown in the present invention being of spider design and of springy metal so that it will retain its shape but yield to the bending of the rubber.

In the drawings:

Figure 1 is a perspective view of the heel portion of a shoe, showing one of the interlocking elements secured in position thereon.

Fig. 2 is a perspective view of a rubber heel embodying my invention.

Fig. 3 is a longitudinal sectional view of the heel of a shoe equipped with the invention.

Fig. 4 is a perspective view of the interlocking element to be cast into the rubber heel.

Fig. 5 is a perspective view of the interlocking element to be pegged to the shoe.

Fig. 6 is a fragmentary top view of the interlocking elements showing the T-head connection as it is initially inserted, and

Fig. 7 is a side view of same showing the parts in locked position.

A designates a shoe, and B a shallow heel thereon, C designates a heel element adapted to coöperate with the shoe element D to lock the rubber heel to the shoe. E designates a rubber heel of usual contour having in its under face a circular recess 1 having a flat bottom 2, said recess being of slightly increased diameter, at its top. Buried in the rubber beneath said bottom, and having a centrally disposed upwardly extending shank or stud 3, protruding centrally through the rubber, is the anchor element D. This anchor element is made of springy steel plate, and is formed with a plurality of short radial arms 4, and a long radial arm 5, bent upwardly at its outer extremity to form a lug 6. The shank 3 is capped with a horizontally disposed T head 7, extending at right angles to the arm 5 and in parallelism with the lug 6. The T head is curved upwardly at its ends, so as to form curved under surfaces 8 (Fig. 7). As illustrated in Fig. 3, the element is slightly spaced from the bottom 2 of the recess 1, the arm 5 extending forwardly longitudinally of the shoe and the tip of the lug 6 protruding slightly above the flat under surface 9, of the rubber heel at a position adjacent the breast 10 of the heel, as is best shown in Fig. 2 of the drawings.

Fitting into the recess 1, so as to be revoluble therein without too great frictional engagement, is the pan shaped element D, the pan portion thereof being of a height measured from its rim edge 12 to the outer side of its bottom 13, equal to the depth of the recess 1, see Fig. 3. Centrally, in the bottom of the pan, is the elongated aperture 14, adapted to receive loosely, the T head 7 so that the latter may be projected therethrough.

Extending in parallelism with the bottom

13, from the edge 12, and in longitudinal alinement, with the aperture 14, is the arm 15, said arm having near its outer end an opening 16, adapted to receive the tip of the lug 6. The lug 6 and the opening 16 lie in a circle concentric with the recess 1, so that when the T head 7 of the heel, is inserted into the aperture 14 of the element on the shoe, (as by placing the heel as indicated by dotted lines in Fig. 1) and the heel is caused to be turned, the tip of the lug will enter the opening 16. Along the edge 12 of the element D are a plurality of upstanding teeth 17. The process of mounting the element D 15 may be described as follows.

The element is inserted in the heel as above described, bringing the arm 15 to a position indicated in Fig. 2. The heel is now held positioned by hand on the shoe to bring its edges flush with the edges of the heel portion on the shoe. A gentle tap with a hammer on the top of the rubber heel will cause the teeth 17 to slightly indent the leather of the shoe. The element D is now removed from the rubber heel and placed back on the shoe, care being taken to have the teeth engage their respective indents in the leather. Pegs or other suitable nails are now inserted in the nail holes 18 and 19 of the element and firmly driven into the leather, the teeth thereby also being driven to bring the edge 12 into engagement with the top of the shoe heel B. Obviously, by employing the teeth 17, the element is easily and quickly correctly positioned, and as the metal of the element is very thin the arm 15 need not be sunk flush into the leather, as the nails in the holes 19 drive the arm into the leather, or in other words, the leather is compressed sufficiently by the blows of the hammer at that point so as to form a hollow place, with respect to the corners a—a of the heel. Thus no cutting of the heel is required. By using a T head as shown, the curved under sides 8 thereof, operate like a wedge against the edges 20 of the apertures 14, when the heel is turned into alining position. As the alining position is approached, the rubber heel is slightly flexed upwardly by hand, to permit the lug 16 to pass over the shoe heel, the spring in the metal of the arm 5 imparting a strong spring stress to the heel.

I claim:

55 1. In an interchangeable heel and means for attaching the same to shoes, the combination with a fixed heel forming part of the shoe, of a flat shallow circular hollow member secured to the surface of the fixed heel and having a thin plate extension lying flat on the fixed heel and extending forwardly to the breast thereof, a rectangular opening in the forward part of said plate extension, an elongated opening cut through the center of 60 the top wall of the circular hollow member

and disposed longitudinally of the fixed heel, a heel normally fitting over said fixed heel and having a projecting lug adapted to engage said rectangular opening when said heel is in normal position, a recess in the heel 70 to the rear of said lug, a T headed stud extending from the bottom of said recess, the head thereof disposed transversely of said heel and projectable through said elongated opening and adapted to interlockingly engage the top wall of the circular hollow member when it is inserted in and turned so as to be positioned at right angles to said elongated opening, and a circular wall for said recess concentric with said T headed 75 stud, said wall slidably peripherally surrounding said circular hollow member, so that said heel may be bodily rotated on the latter and normally held against lateral displacement. 80

2. In a device of the class described, the combination with a fixed shoe heel, a circular flat topped hollow metallic member secured to the fixed heel, and having a thin plate extension lying flat on the heel and extending forwardly to the breast thereof, an opening in said plate extension near the end thereof, a rubber heel normally fitting over said fixed heel having a recess fitting over the body of said hollow member so that said rubber heel may be bodily rotated thereon and also held against lateral shifting, a lug on the rubber heel engaging said opening when the heel is in normal position, an elongated opening cutting through the top of 90 said hollow member, and a T headed stud centrally in said recess, and extending with its head through said elongated opening, the head thereof projectable through the latter and normally positioned at right angles 95 thereto to hold the rubber heel locked to the fixed heel. 100

3. In a detachable heel to be used in connection with a fixed heel, a circular flat hollow element having an elongated opening in 110 its top and formed with an extending part having a perforation near its end, said element adapted to be secured to the fixed heel, a rubber heel having a recess revolvably receiving said flat hollow element, means extending outwardly from the rubber heel for engaging said elongated opening and said perforation to detachably hold the flat hollow element locked against rotary and outward movement, and teeth extending downwardly from the under side of the hollow element for the purpose set forth. 115

4. In a detachable heel to be used in connection with a fixed heel, a circular flat hollow member having an elongated opening in 120 its top and formed with an extending part having a perforation near its outer end, said element being adapted to be secured to the fixed heel, a rubber heel having a recess revolvably receiving said flat hollow element, a 125

T headed stud and a lug extending outwardly in spaced relation from the rubber heel, for engaging respectively said elongated opening and said perforation whereby to detachably hold said hollow element against rotary and outward movement, and a long narrow spring steel plate buried in the rubber heel and connecting said T headed stud and said lug to permit the latter to be moved against the stress of the spring 10 steel plate for the purpose set forth.

In testimony whereof I affix my signature.

STANLEY SOLARZ.
